HAND TRUCK

George W. Burg, Portland, Oreg.

Application March 18, 1946, Serial No. 655,230

5 Claims. (Cl. 280—57)

1

My invention relates to a stock pick-up and carrier truck specifically adapted for handling elongated sections of material, such for example, as tubes or pipes, sheets of plate, sheets of plywood and also is adapted to carry relatively narrow, heavy packages, such for example, as boxes.

It is common practice to transport said articles in packages or bundles and a truck of this character must be capable of picking up a relatively heavy bundle or package from the floor and arranging it automatically to balance itself upon the truck so that said truck will not tend to overturn. This should be accomplished independent of the dimensions of the package or the weight thereof within limits.

A principal object of my invention is to improve that type of stock pick-up and carrier truck described in my co-pending application for patent, entitled Stock Pick-up and Carrier Truck, which was filed in the United States Patent Office January 30, 1945, and which bears Serial No. 575,212 and has since issued as Patent No. 2,466,149, dated April 5, 1949.

The stock pick-up and carrier truck described in said co-pending application for patent is capable of picking up and transporting bulky packages, such for example, as sheets of plywood, metal, boards, and the like when they are arranged on edge and to arrange the weight thereof so that one man may push the truck over a floor and to discharge it without requiring additional help. It has a disadvantage, however, in that it does not lend itself to picking up and transporting heavy, bulky packages nor to carry bundles of pipe, tubing and the like with as great facility and with the ease that it does in transporting sheets of material for which it is specifically adapted.

I attain this principal object of my invention by providing a truck having a base and vertically extending load supporting members with two or more obliquely disposed members bearing upon the vertical members and leading from the forward edge of the base to the top thereof and shaped so that they will carry narrow, short packages with as great facility as larger, more bulky and less massive sheets. This is accomplished in my present invention by forming said obliquely disposed members with a lower portion which, although oblique and a substantial vertical component, does not extend at as sharp a vertical angle as does the upper portion thereof. An intermediate section of said oblique members is arranged vertical and in abutment with the vertical members extending from the trailing

2

edge of the base. When formed in this manner, the load supporting members will support narrow, bulky packages on said lower end with the center of mass thereof arranged intermediate the casters, so as to resist overturning. They also will support longer, more elongated packages upon load-engaging hooks, said elongated packages resting against the upper, more vertically inclined members. Said truck, because of the arrangement of said load supporting members, may support a pair of work-engaging hooks intermediate the ends of said oblique load supporting members and immediately below the vertical intermediate section. The load supporting members form virtual pockets for accommodating a load supported by said hooks with the load carried thereby arranged substantially at the longitudinal center line of the base, thus, being substantially equally supported by the four casters which support said base.

A further object of my invention is to arrange said load supporting members and said hook, last described, so that the latter may be easily and quickly engaged therewith to support a load or 25 to be swung out of operating position so that said truck is adapted to accommodate other and different loads carried by said truck.

A further and more specific object of my invention is to provide a truck of this character, having a plurality of load-engaging elements which may be moved selectively into and out of operating position to position a load of selected mass and dimensions centrally upon said truck so that it is laterally stable so as not to tend to overturn said truck when the latter is moved about a floor.

The details of my invention and the mode of operation thereof are hereinafter described with reference to the accompanying drawings, in which:

Fig. 1 is a perspective view of a truck embodying my invention in which the left-hand load engaging hook is illustrated as being in operating position to engage a load intermediate the ends of the oblique load supporting member and the load engaging hook at the right-hand side is adapted to engage a relatively wide package and other load engaging devices are reversely arranged; it is to be understood that there are pairs of load engaging members at each end of said device and like pairs are moved into position and other load engaging members are swung into inoperative position with respect thereto;

Fig. 2 is a side elevation of the truck embodying my invention with a load engaging element

shown swung into operating position to support a relatively massive compact bundle lying below the intermediate vertical section of the oblique members;

Fig. 3 is a view similar to Fig. 2 except that load engaging members are arranged intermediate the ends of the oblique load supporting member, such for supporting sections of pipe or tubing, immediately below the vertical portion of an oblique load supporting member;

Fig. 4 is a view similar to the two foregoing views with the load supporting members arranged to accommodate a relatively wide bundle extending the full height of the oblique load supporting member; and

Fig. 5 is a sectional view taken on the line 5—5 in Fig. 4, illustrating the construction of a load-supporting arm and its bracket.

A hand truck embodying my invention comprises a base 1 preferably comprising a longitudinal member 1a extending the full width of the truck and two laterally extending members 1b joined to the longitudinal member and projecting rearwardly therefrom. That is, said base preferably is open in the back considering the back is the trailing portion or one side thereof where the operator stands to push the truck, said frame being open to permit him to step between the casters 2 supporting the frame, not only to steady said hand truck but also to place his foot immediately adjacent the longitudinal member 1a when a load is being lifted by the downwardly projecting nose pieces 3, secured to the frame immediately under the longitudinal member 1a. Said members 1a and 1b are joined together by diagonal bracing members 1c. The casters 2 are supported by pads 4. Said casters usually are four in number and are arranged at the ends of the lateral members 1b and the point of juncture of said lateral members with the longitudinal members.

A plurality of obliquely disposed load supporting members 5 are secured to the longitudinal member 1a of the base defining the other side of the base and extend upwardly to a point overlying the trailing extremities of the laterally extending members 1b. Vertical members 6 are secured to said rearward or trailing ends of said lateral extending members 1b and are secured at their upper ends to the oblique load supporting members 5 at a point intermediate the ends of said members 5. Thus, said members 5 extend over the top of said vertical members, as is shown in the several views of the drawings. The upper ends of said oblique load supporting members preferably are joined by a longitudinal load supporting member 7. The several load supporting members and the frame are preferably joined together by welding so as to produce a strong and rigid frame. Said base and load supporting members preferably are made of tubular stock so as to attain substantial rigidity and strength without substantial weight. If a hand truck of substantial width is provided, I provide three of said oblique supporting members 5, the two end ones being joined to the vertical members and the central one 5a having a handle or grip 8 formed thereon. Said handle or grip may be used by the operator in pushing said truck along or in directing its course.

One of the more important features of my present invention is to form said oblique load supporting members so as to accommodate different types of loads. That is, said oblique load supporting members are adapted to accommodate

themselves to narrow, compact heavy loads, wider lighter loads, or lengths of stock, such for example, as tube or pipe, which are unwieldy because of their flexibility and length. It is essential that the center of mass of any given load lie at a point between the casters so that the truck will not be overturned by said load. Thus,

although the general plane of said oblique load supporting members 5 extends obliquely across the base 1, the lower portion 5b is inclined at a lesser vertical angle than the upper portion 5c. Joining said oblique portions 5b and 5c in each member 5 is a vertical portion 5d in each of the members 5. Thus, if a heavy compact load 9, as shown in Fig. 2, is to be handled by said truck, it will lie wholly within that portion of the oblique load supporting member below the vertical portion 5d, and the center of mass will lie substantially rearwardly of the plane of the forward casters supporting said base. To accommodate such load, I provide a pair of pivotally mounted load supporting hooks 10, pivotally joined to the base by bolts or studs 11 and having a forward upwardly inclined nose 12 which when said hooks 10 are arranged as viewed in Fig. 2 extends substantially normal to the plane of the lower portion 5b of the members 5. When said load supporting hooks are to be swung into out-of-the-way position they overlie the diagonal bracing members 1c and are held in alignment therewith by clips 13 secured to said bracing members 1c, as is viewed in Fig. 1.

If a relatively light elongated load is to be carried, such as one comprising pipes or tubes 14, said load may be supported by cradle-like load supporting arms 15, each carried by a bracket 16. Said brackets have curved ends 16a, adapted partially to encircle and grip the members 5 and 6 at a point slightly below the vertical portions 5d of the members 5, as is illustrated in Fig. 3. Said curved ends are divergent to engage and position said brackets securely. The upper end 6a of each vertical member 6 is in abutment with the vertical portion 5d of a member 5 and said parts preferably are welded together so as to produce a solid, rigid structure at this point. Said vertical members thus support any load which tends to rock the oblique members 5 clockwise about the lower end thereof, as said parts are arranged in Figs. 2, 3 and 4. Such arrangement also causes said parts to be joined securely to provide a rigid structure for supporting a load when it is carried by the brackets and cradle-like load supporting arms 15, as is illustrated in Fig. 3.

When the load supporting arms and brackets are to be moved into inoperative position, this may be accomplished by arranging said parts in the manner shown in the right-hand portion of the frame in Fig. 1 and as is illustrated in Fig. 4. One of said curved ends engages a vertical member 6 and the points of the cradle-like supporting arms are arranged in cups 17 arranged, respectively, adjacent the points of juncture of the base members 1a and 1b. In this position, they are firmly supported and are not subject to become lost by vibration or rough handling.

When a load, such as is illustrated in Fig. 4 and designated as 18, is to be handled which is substantially as wide as the height of the oblique members 5, this may be accommodated by supporting said load upon the nose pieces 3 and permitting the upper end thereof to rest against the upper portions 5c of the oblique load supporting members 5.

It is possible to lift a load 18 by the nose pieces

3 or to lift a load 9 by the load supporting hooks 10, although the latter requires the hand truck to be moved so the oblique portions 5 extend substantially vertically or possibly tip forward upon the nose pieces 3 even further than that to engage such a load. Because of the proportions of the parts, however, said load may be lifted in place because of the leverage provided by the load supporting members with respect to the height of the base from the floor or ground level.

My hand truck, thus, is adapted to accommodate itself to any one of a number of different types, sizes and weights of loads and the load engaging members are selectively engageable with a load and may be easily and quickly moved out of disengaging position if other or different load engaging members are to be moved into operating position. It is to be noted that the nose pieces 3 are fastened to the base and are not swung out of operating position. The load engaging hooks 10, however, are adapted to swing so as substantially to overlie them and said hooks extend outwardly beyond the nose pieces 3 so that said nose pieces 3, when the hooks are swung into the position shown in Fig. 2, are effectively out of operating position although they have not been moved.

I claim:

1. A hand truck comprising an elongated horizontally disposed base having two sides, casters supporting said base, a load supporting frame carried by said base and comprising a pair of vertically extending members projecting upwardly from one side of said base, and obliquely extending load supporting members inclined upwardly from the other side of said base across said base and joined to each of said vertical members, said obliquely extending members having their lower portions extending at a lesser vertical angle than that of the upper portions thereof, and a plurality of load engaging members selectively engaging the several portions of said oblique members for supporting loads of diverse shapes against selected portions of said oblique members.

2. A hand truck comprising an elongated horizontally disposed base having two sides, casters supporting said base, a load supporting frame carried by said base and comprising a pair of vertically extending members projecting upwardly from one side of said base, and obliquely extending load supporting members inclined upwardly from the other side of said base across said base and joined to each of said vertical members, said obliquely extending members having their lower portions extending at a lesser vertical angle than that of the upper portions thereof, said portions being joined by an intermediate section extending substantially vertically, and a plurality of load engaging members selectively engaging the several portions of said oblique members for supporting loads of diverse shapes against selected portions of said oblique members.

3. A hand truck comprising an elongated horizontally disposed base having two sides, casters supporting said base, a load supporting frame carried by said base and comprising a pair of vertically extending members projecting upwardly from one side of said base, and obliquely extending load supporting members inclined upwardly from the other side of said base across

said base and joined to each of said vertical members, said obliquely extending members having their lower portions extending at a lesser vertical angle than that of the upper portions thereof, each of said lower and upper portions of each of said members being joined by an intermediate section extending substantially vertically and lying in abutment with and parallel to a corresponding vertical member, and a plurality of load engaging members selectively engaging the several portions of said oblique members for supporting loads of diverse shapes against selected portions of said oblique members.

4. A hand truck comprising an elongated horizontally disposed base having two sides, casters supporting said base, a load supporting frame carried by said base and comprising a pair of vertically extending members projecting upwardly from one side of said base, and obliquely extending load supporting members inclined upwardly from the other side of said base across said base and joined to each of said vertical members, said obliquely extending members having their lower portions extending at a lesser vertical angle than that of the upper portions thereof, each of said lower and upper portions of each of said members being joined by an intermediate section extending substantially vertically and lying in abutment with and parallel to a corresponding vertical member, a plurality of load engaging members selectively engaging the several portions of said oblique members, one of said load engaging members detachably gripping said oblique and vertical members, the gripping portions being spaced to seat the latter load engaging member a predetermined distance below the vertical intermediate section of said oblique load supporting members.

5. A hand truck comprising an elongated horizontally disposed base having two sides, casters supporting said base, a load supporting frame carried by said base and comprising a pair of vertically extending members projecting upwardly from one side of said base, and obliquely extending load supporting members inclined upwardly from the other side of said base across said base, being joined to each of said vertical members and extending over the top thereof, said obliquely extending members having their lower portions extending at a lesser vertical angle than that of the upper portions thereof, and a plurality of load engaging members selectively engaging the several portions of said oblique members for supporting loads of diverse shapes against selected portions of said oblique members.
